Primary Examiner — Sandra S Snapp*Assistant Examiner* — Ieisha N Price(74) *Attorney, Agent, or Firm* — Schwabe Williamson & Wyatt, P.C.(57) **CLAIM**

We claim the ornamental design for a bumper drive link, as shown and described.

DESCRIPTION

FIG. 1 is a perspective view of a bumper drive link showing our new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The dash-dot-dot-broken line immediately adjacent to the shaded area represents an unclaimed boundary of the claimed design. The remainder of the broken lines are provided for environmental purposes only and form no part of the claimed design.
